[57] CLAIM

The ornamental design for a livestock dip vat, substantially as shown and described.

DESCRIPTION

FIG. 1 is a top plan view of the livestock dip vat, showing my new design;

FIG. 2 is a bottom plan view thereof;

FIG. 3 is a front elevational view thereof;

FIG. 4 is a rear elevational view thereof; and

FIG. 5 is a left side elevational view thereof, the right side being a mirror image of the side shown.

FIG. 5

FIG. 2

FIG. 1

FIG. 4

FIG. 3
